UNITED STATES PATENT OFFICE.

OSMOND FERGUSSON, OF LONDON, ENGLAND.

LAMP.

SPECIFICATION forming part of Letters Patent No. 488,711, dated December 27, 1892.

Application filed April 19, 1892. Serial No. 429,812. (No model.)

To all whom it may concern:

Be it known that I, OSMOND FERGUSSON, merchant, a subject of the Queen of Great Britain and Ireland, residing at 190 Eglinton 5 Road, Woolwich, London, England, have invented an Improved Traveling Lamp, of which the following is a specification.

This invention relates to an improved lamp for use when traveling, which may be attached 10 to a book or other article, and has for its object to provide a lamp adapted for this purpose which will give a clear and uniform light for some time and be of very cheap construction, so that a fresh lamp may be used when 15 one has burned out.

The complete lamp consists of two parts, the lamp or container for the wick and wax or oil, and a holder for the lamp. The holder is stamped or otherwise formed out of a single 20 piece of thin sheet metal, such as tin, and comprises a reflector, means for supporting the lamp, a book clip and a hook for suspending. The lamp is formed from two pieces of metal, concave, with a rim, the rim 25 of one piece being larger than that of the other and bent round it forming a circular container, with a suitable neck through which the wick passes.

Referring to the accompanying sheet of 30 drawings, which illustrate my invention, Figure 1 shows the holder as stamped out, before being made ready for the lamp, Figs. 2 and 3 are respectively a front and side elevation of the lamp and holder complete, and 35 Fig. 4 is a plan of the lamp or container.

1 is the upper circular part forming the reflector, being made concave in order to direct the light better, and having at its top a small projecting piece 2, turned over to form 40 a hook. At the lower part of the holder is the book clip 3, formed by the tongue 4 stamped out of the enlarged end, connected to the reflector by the narrow strip 5.

6, 6 are two arms projecting from each side 45 of the connecting strip at a short distance below the reflector and 7 is a small tongue a little lower down.

8 is the lamp or container with neck 9 at top, the flange being formed by the rims 50 above mentioned. The neck as shown in Fig. 4 is six sided forming an opening, wedge

shaped, on either side of the wick. This allows air to penetrate to the interior of the container as the contents are consumed. The container is filled with a mixture of wax and oil, which melts at a low temperature, but is solid when the lamp is not in use. This is poured into the container hot, and a wick after being steeped in wax and allowed to cool is inserted through the neck reaching to 55 the bottom of the container and projecting a little through the neck. The arms 6 are bent round in front, their ends being turned so that they retain the flanges of the lamp and the tongue 7 is bent at right angles, the 60 lamp 8 being slipped between the ends of the arms 6 and supported on the tongue 7.

In using the lamp, it is attached to the book or other article desired to be illuminated, by means of the clip, or is suspended in any suitable manner by the hook 2.

What I claim as my invention, and desire to secure by Letters Patent is:—

1. In a traveling lamp, the combination of the reflector 1 hook clip 3 connecting strip 5, 75 supporting arms 6 and tongue 7, all formed from one piece of metal with a lamp or container 8 held by the arms 6 and tongue 7 substantially as described and shown.

2. In a traveling lamp the combination of 80 a reflector 1, hook 2, supporting arms 6, and tongue 7, projecting from the part 5, all formed from a single piece of metal, with a lamp or container 8, held by the arms 6 and tongue 7, and formed of two pieces of concave metal, each having a rim and projecting piece, one rim being bent round the other, forming a hollow case with a neck at the edge, formed by the projecting pieces through which the wick extends.

3. A container 8, formed of two pieces of concave metal each having a rim and projecting piece, one rim being bent round the other, forming a hollow case with a neck 9 having a wedge shaped opening on either side of the 95 wick as shown for the purpose specified.

In witness whereof I have hereunto set my hand in the presence of two witnesses.

OSMOND FERGUSSON.

In presence of—

JAMES MILLER,

ALBERT EDWARD ELLEN.
